UNITED STATES PATENT OFFICE.

ALBERT D. PARFITT, OF CHICAGO, ILLINOIS.

REBUS MOTION-PICTURE FILM.

1,277,468.

Specification of Letters Patent. Patented Sept. 3, 1918.

Application filed September 5, 1916. Serial No. 118,408.

To all whom it may concern:

Be it known that I, ALBERT D. PARFITT, citizen of the United States, residing at Chicago, in the county of Cook and State of Illinois, have invented certain new and useful Improvements in Rebus Motion-Picture Films; and I do hereby declare the following to be a full, clear, and exact description of the invention, such as will enable others skilled in the art to which it appertains to make and use the same.

My invention relates to the production upon a screen of animated puzzle pictures, one of its general objects being that of providing a method by which the solution of the puzzle may be suggested to the spectator continuously, or at least for a prolonged period during the display of the pictures which present the puzzle. Another general object is that of providing a film suitable for use in standard types of motion picture projectors for displaying a series of apparently animated pictures affording the aforesaid effect; that is to say, a motion picture film presenting a series of pictures which consecutively display the constituent elements of the puzzle and which continuously display a suitable clew to the solution of the puzzle. Further objects will appear hereafter.

While my invention may be utilized merely as a means of entertainment or mental diversion, it also lends itself effectively to use as a means of advertising, for which latter purpose the pictures may desirably be so designed that the solution of the puzzle names a certain product, or a slogan relating to a certain advertised brand of goods. When thus utilized, I have found it quite common (even in theaters where the patrons paid the regular admission price) for a considerable portion of the audience to whisper the component parts of the puzzle as these parts were presented; and where a series of such puzzle films were successively presented, I have found a considerable part of the audience willing to write the solution (or assumed solution) of each puzzle on blanks provided for that purpose. In either case, I have obtained the effect for which advertisers have long striven in vain, namely that of inducing a large number of persons while assembled in a public place to enunciate and even to write the name of the advertiser or of his distinctive goods.

In employing my invention for advertis-

ing purposes, I have found it desirable to use the rebus and charade types of puzzle pictures, and am therefore illustrating such a form in my drawings. However, I do not wish to be limited to any particular type and am using the term rebus in the broad sense in which it might include various other forms of puzzle pictures. If a standard motion picture machine is used, I employ a film of transparent material; but if the projecting is to be done by a lantern operating on the projection principle, I employ paper or other opaque material. In either case, I imprint the sections of the film with consecutively slightly dissimilar pictures so arranged as to simulate motion upon at least a portion of the screen when the film is projected upon the latter, and preferably include among the apparently animated picture portions some of the constituent elements of the rebus. I also include in a considerable number of consecutive film sections (and preferably at least in the earlier sections) an element adapted to give a clew to the solution of the rebus, which clew will thus be continuously displayed during the gradual presentation of the component parts of the puzzle picture.

For example, if my invention is to be employed for advertising the socalled "Sun-kist" brand of oranges, the initial, middle and final sections of the film may be as shown respectively in Figs. 1, 2 and 3 of the drawings. In this case, the presence of the crate in the pictures, and the emphasis placed upon the crate both by its conspicuous position in the initial film section and by the question mark on the crate, all imply that this crate has something to do with the solution of the puzzle. Then the rising of the sun introduces the latter, the growing of the tree gives an animated effect to the presentation and introduces the oranges, the flying of an orange from the tree to the lips of the sun suggests the term "sun-kissed" (which term of course must be familiar to the spectators to make such a puzzle presentation effective for advertising purposes), and the flying of the orange or oranges from the sun into the crate links both the sun-kissing and the oranges in an appropriate manner with the crate which persistently faces the spectator and suggests that its possible contents may have something to do with the solution of the puzzle. To make the clew-suggesting function of the

crate still more effective, I may employ auxiliary means, as for example by initially presenting a conspicuous question-mark on the end of the crate and gradually having this fade away during the presentation of the later film sections, thus gradually transferring the attention of the observer from this question mark to the oranges in the crate. In other words, the question mark displayed upon the crate during the earlier film sections affords one clew to the desired solution, the oranges shown in the crate during the latter film sections afford a second clew, and the first of these clews gradually vanishes during the presentation of the second clew.

However, while I have shown and described an embodiment of my invention including pictorial presentations, I do not wish to be limited to this or other details of the construction and arrangement herein disclosed, it being obvious that the same might be modified in many ways without departing from the spirit of my invention.

I claim as new:

1. The method of displaying a rebus upon a picture screen, which consists in continuously projecting a clew to the solution of the rebus thereon, and simultaneously and pro-

gressively developing the remaining clews of the rebus one of which is finally associated with the continuously projected clew to effect solution of the rebus.

2. The method of displaying a rebus upon a picture screen, which consists in continuously projecting a clew to the solution of the rebus thereon, initially projecting a second clew and subsequently and progressively obliterating said second clew, and simultaneously and progressively with said obliteration developing the remaining clews of the rebus one of which is finally substituted for the obliterated clew.

3. A rebus film for motion picture machines, comprising a series of film sections each displaying a clew to the solution of the rebus, said sections also containing portions progressively developing the remaining clews of the rebus and coöperating with the first named clew in presenting a solution of the rebus.

4. A rebus film as per claim 3, in which the matter on the film sections is so arranged that the first named clew is gradually obliterated during the developing of the said remaining clews.

ALBERT D. PARFITT.
